UNITED STATES PATENT OFFICE.

BENNO J. BONGARTZ, OF BROOKLYN, NEW YORK, ASSIGNEE TO UNITED STATES AIR CRAFT CORPORATION, INC., OF NEW YORK, N. Y.

AVIATOR'S INSTRUCTION-MACHINE.

1,272,768.

Specification of Letters Patent. Patented July 16, 1918.

Application filed July 3, 1917. Serial No. 178,497.

To all whom it may concern:

Be it known that I, BENNO J. BONGARTZ, a citizen of the United States, residing at Brooklyn, in the county of Kings and State 5 of New York, have invented new and useful Improvements in Aviators' Instruction-Machines, of which the following is a specification.

This invention relates to aviators' instruction machines, the broad object of the invention being to produce an effective machine for instruction purposes which will enable aviators to obtain a thorough understanding and manipulation of the controls 15 of an aeroplane either for land or water uses, without leaving the ground or surface of the water and thereby running unnecessary risks during the initial study period.

A further object of the invention is to produce a machine of the general character referred to by means of which one of the controls may be acquired at a time thus greatly simplifying the work of the student and enabling him to acquire confidence more rapidly than he otherwise could, were he compelled to simultaneously acquire all of the control movements.

More specifically stated, the object of the invention is to produce an instruction machine in which the steering operation may be first acquired, followed by the acquisition of the fore and aft balancing operation, to be succeeded by the acquirement of the lateral balancing operation.

With the above and other objects in view, the invention consists in the novel construction, combination and arrangement of parts, herein fully described, illustrated and claimed.

In the accompanying drawings:—

Figure 1 is a plan view of the instruction machine.

Fig. 2 is a side elevation of the same.

Fig. 3 is a front elevation thereof.

The instruction machine contemplated in this invention comprises a body or fuselage 1, a tractor propeller 2, a horizontal rudder 3, a vertical rudder 4, and lateral balancing planes or ailerons 5.

In a simple embodiment of the invention, a transversely extending beam or spar 6 is rigidly fastened to the body 1 and extends equally on opposite sides thereof, the ailerons 5 being attached to the end portions 55 of the spar 6 and being either of the hinged or flexible type. No aerial supporting sur-

face is provided, as it is not intended that the machine shall be used for actual flight but only on the ground or surface of the water in order to insure the safety of the student aviator. The aviator's seat 7 is supported upon or within the body 1 and in convenient relation to a steering column 8 provided with the usual hand control wheel 9. Lateral balancing connections 10 lead from the column 8 to the ailerons 5 and are so arranged that said ailerons or lateral balancing planes may be swung or moved upwardly and downwardly, simultaneously in opposite directions. Other connections 11 lead from the steering column to the vertical rudder, and still other connections 12 lead from the steering column to the horizontal rudder.

The machine thus far described is adapted to be supported by a number of wheels. Front and rear wheels 13 and 14 are arranged under the body 1 in advance and in rear of the aviator's seat and also in advance and in rear of the transverse aileron 80 carrying spar 6. A third wheel 15 is arranged centrally beneath the body 1 between the wheels 13 and 14 and approximately in line with the center of gravity of the machine when the operator is seated therein. Other wheels 16 are arranged at opposite sides of the body and equi-distantly from the center thereof, the wheels 16 having the same function as the ordinary ground wheels of a land aeroplane.

Each of the wheels 13, 14, 15 and 16, hereinabove referred to, is mounted in a hanger or bearing post 17 and is adjustable up and down therein, being held in its adjusted position by fastening means 18. This enables each of said wheels to be adjusted in height without affecting the other wheels.

In the initial operation of the machine, it being understood that said machine is equipped with an engine for driving the propeller 2, all of the wheels with the exception of the front and rear wheels 13 and 14 are elevated so as not to contact with the ground, the machine being then supported solely by the front and rear wheels 13 and 14. The rear wheel 14 is controlled by the same connections 11 which control the vertical rudder 4. The machine is now operated in the same manner as a motor-cycle, the wheel 14 being journaled so as to turn on a substantially vertical axis. The machine is thus steered in the same manner as

- a bicycle and if desired the ailerons may be simultaneously utilized for lateral balancing purposes. After the student acquires the lateral balancing of the machine, the front 5 and rear wheels 13 and 14 are elevated and the central wheel is left elevated, the wheels 16 being lowered and then forming the only wheels upon which the machine is supported. By operating the horizontal rudder 3, 10 the aviator is now enabled to acquire the fore and aft balance or equilibrium. After he has advanced sufficiently far, all of the wheels are elevated with the exception of the single central wheel 15 and now the student 15 learns to simultaneously control the fore and aft and the lateral balance as well as the directional steering of the machine by means of the vertical rudder, the steering wheel 14 being now out of contact with the ground. 20 By means of the construction and arrangement hereinabove described, the student aviator acquires the controls gradually, one at a time, and thus acquires confidence in his ability to handle an aeroplane 25 and this is accomplished with absolute safety to the student and also without the many mishaps and partial or total destruction of an aeroplane when the latter is used for instruction purposes. 30 In lieu of the supporting wheels hereinabove described, floats, pontoons, or the like may be substituted for said wheels and made practically adjustable for the purpose hereinabove described in connection with the 35 wheels, thereby enabling the student aviator to acquire all of the controls of the machine while skimming along the surface of the water and without rising therefrom. The floats or pontoons referred to are designated at 13', 14', 15' and 16' corresponding 40 with the respective wheels 13, 14, 15 and 16.
- I claim:
1. An aviator's instruction machine, comprising a body, an engine driven propeller, lateral balancing means, fore and aft balancing means, steering means, and supporting base elements, certain of which are adapted to be raised and lowered with respect to the body of the machine and the surface on which the machine is being operated, said supporting base elements comprising a plurality of members arranged in a central fore and aft line with relation to the body of the machine, and means for independently adjusting the last named elements up and down, for the purpose specified.
  2. An aviator's instruction machine, comprising a body, an engine driven propeller, a horizontal rudder, a vertical rudder, lateral balancing surfaces, manually controlled means for operating said vertical rudder, horizontal rudder and lateral balancing surfaces, supporting base elements, certain of which are adapted to be raised and lowered with respect to the body of the machine and the surface on which the machine is being operated, said supporting base elements comprising a plurality of members arranged in a central fore and aft line with relation to the body of the machine and means for independently adjusting the last named elements up and down, for the purpose specified.
  3. An aviator's instruction machine, comprising a body, an engine driven propeller, a horizontal rudder, a vertical rudder, lateral balancing surfaces, manually controlled means for operating said vertical rudder, horizontal rudder and lateral balancing surfaces, and supporting base elements, certain of which are adapted to be raised and lowered with respect to the body of the machine and the surface on which the machine is being operated, said supporting base elements comprising one or more members located in line with the fore and aft axis of the body, and other elements located at opposite sides of the body and equidistantly from the longitudinal axis thereof, each of said elements being independently adjustable up and down, for the purpose specified.
  4. An aviator's instruction machine, comprising a body, an engine driven propeller, a horizontal rudder, a vertical rudder, lateral balancing surfaces, manually controlled means for operating said vertical rudder, horizontal rudder and lateral balancing surfaces, and supporting base elements, certain of which are adapted to be raised and lowered with respect to the body of the machine and the surface on which the machine is being operated, one of said supporting base elements being mounted for steering movement.
  5. An aviator's instruction machine, comprising a body, an engine driven propeller, a horizontal rudder, a vertical rudder, lateral balancing surfaces, manually controlled means for operating said vertical rudder, horizontal rudder and lateral balancing surfaces, and supporting base elements, certain of which are adapted to be raised and lowered with respect to the body of the machine and the surface on which the machine is being operated, one of said supporting base elements being mounted for steering movement and being controlled by the same means used for controlling the vertical rudder.

In testimony whereof I affix my signature.
BENNO J. BONGARTZ.
